UNITED STATES PATENT OFFICE.

ALBERT A. HUSEBY, OF CHICAGO, ILLINOIS.

REPRODUCER FOR TALKING-MACHINES.

1,308,358.

Specification of Letters Patent.

Patented July 1, 1919.

Application filed April 18, 1917. Serial No. 162,877.

To all whom it may concern:

Be it known that I, ALBERT A. HUSEBY, a citizen of the United States, residing at Chicago, in the county of Cook and State 5 of Illinois, have invented certain new and useful Improvements in Reproducers for Talking-Machines, of which the following is a specification.

This invention relates to improvements in 10 reproducers for talking machines, and has reference more particularly to that type of reproducers commonly known as universal reproducers or sound-boxes, which are adapted to play records of both the vertically and 15 laterally cut types. Such universal reproducers are themselves distinguished by typical variations of structure and manner of use. Most of them involve a change of angular position of the sound-box relatively to 20 the tone arm when changing from one type of record to the other. Of these latter, some employ a single stylus-socket with a single stylus therein, others a single stylus socket with interchangeable styli, others a pair of 25 stylus sockets with a single stylus that may be used in either socket, and still others two stylus sockets with styli individual to each socket. Those reproducers which do not involve a change of angular position of the 30 sound-box relatively to the tone arm when changing from one type of record to the other employ a pair of stylus sockets with styli individual to each socket; but the socket for the stylus that plays the vertically 35 cut record is formed in an attachment member that is detachably secured in the other socket.

The reproducer of my present invention belongs to that class which does not require 40 any angular change of position of the sound-box, but employs two permanently attached socket members or stylus holders, so that all that is required to adapt the reproducer to play either type of record is to insert the 45 appropriate stylus in the proper stylus holder and then lower the reproducer into playing engagement with the groove of the record disk.

Furthermore, in playing different types 50 and makes of records it is desirable, in order to secure the best results, to weight the sound-boxes differently on the records. For instance, in playing a Pathe record, the grooves of which are comparatively round 55 and shallow, with a Pathe stylus it is desirable to place more weight on the sound-

box than when playing an Edison record with a sharp-pointed Edison needle; whereas the playing of a Victor or Columbia record calls for a weighting of the sound-box 60 intermediate the weights preferably used in playing the Pathe and the Edison records respectively. The principal feature of my present invention, therefore, resides in the combination with the usual swiveled free end 65 section of the tone arm, of an adjustable weight which may be set to either side of the axis of the swiveled section of the tone-arm so as to increase or diminish the gravity effect of the sound-box and swiveled tone- 70 arm section on the record.

My invention, its mode of operation, and the advantages inhering therein will all be readily understood by those familiar with this art from a consideration of the following description taken in connection with the accompanying drawing wherein I have illustrated several practical and approved embodiments of the invention, and in which—

Figure 1 is an elevation, broken out, of 80 the usual swiveled extension of the tone-arm and the sound-box connected to the latter, showing my present improvements applied thereto;

Fig. 2 is a similar view, partly in vertical 85 section, as seen from the right of Fig. 1;

Fig. 3 is a face elevation of the sound-box, illustrating a modification;

Fig. 4 is a view similar to Fig. 3 illustrating another modification.

Referring to the drawing, 5 designates the tone-arm in which is swiveled the usual downwardly and laterally offset tone-arm extension 6, to the free end of which latter is coupled the sound-box designated as an entirety by 7. On the lower side of the sound-box are a pair of forwardly extending lugs 8 carrying pointed pintles 9 on and between which is mounted a fulcrum bar 10. At one end of the fulcrum bar 10 is a downwardly 95 extending socket-piece 11 that is inclined to the axis of the fulcrum-bar and is adapted to receive a needle or stylus 12 in its lower end suitable for playing records of the laterally cut type. At the other end of the fulcrum bar 10 is a horizontally extending 100 socket-piece 13 disposed at a right angle to the axis of the fulcrum-bar and having a transverse socket 14 adapted to receive a needle or stylus suitable for playing records 110 of the vertically cut type. Both of the socket-pieces 11 and 13 are permanently and

rigidly associated with the fulcrum bar 10, as by being soldered thereto, and constitute permanent elements of the sound-box structure. Rigidly connected to the fulcrum bar 10 is a stylus arm, the upper end of which is connected to the center of the usual diaphragm of the sound-box. In Figs. 1 and 2 this stylus arm 15 is connected to the fulcrum bar in alinement with the socket-piece 11, being conveniently and preferably integral with the latter, as shown. In Fig. 3 the stylus arm 15' is connected to the fulcrum bar 10 at a point coincident with the inner end of the horizontal socket-piece 13, and may conveniently be formed integral with the latter. In Fig. 4 the stylus arm 15" is rigidly connected to the fulcrum bar 10 at a point substantially midway between the socket pieces 11 and 13, the lower end of the stylus arm being conveniently apertured for the passage therethrough of the fulcrum bar, and being secured on the latter by a setscrew 16. It will be noted that in all three forms illustrated the stylus arm is rigid with the fulcrum bar, and the two stylus sockets are also permanently and rigidly attached to or associated with the fulcrum bar. When a stylus is inserted in either socket-piece and brought into contact with the record, the other empty socket piece is sufficiently elevated above the record to be out of the way.

Referring to that feature of the invention which relates to the adjustment of the weight of the sound-box on the record when playing different styles of records, this feature as herein shown is embodied in a pivoted counterweighted disk so mounted on the elbow extension of the tone-arm that the weighted portion of the disk can be shifted to extreme positions on opposite sides of the longitudinal axis of the swivel joint or to an intermediate position. Referring to the drawing, on the depending portion 6' of the tone-arm extension 6 are a pair of tapped lugs 17 and 18. 19 designates a knob, the shank of which has a squared portion 20 and a round portion 21, this knob being secured to the face of the lug 17 by a screw 22 passing therethrough. 50 Mounted on the squared portion 20 of the shank of the knob is a disk 23 carrying on its rear side a segment-shaped counterweight 24. This disk is cut away on the lower portion of its periphery, as indicated in Fig. 1, thereby providing radial stop shoulders 25 and 26. 27 designates a stationary disk that is centrally apertured to fit the round portion 21 of the shank of the knob and on its lower side receives a screw 28 that enters the tapped lug 18 to lock said disk 27 against turning. In the upper portion of the disk 27 is a sight opening 29. On the opposite face of the counterweighted disk 23 are printed the names of different types of records, such as "Pathé,"

"Victor" and "Edison," as indicated in Fig. 1. When a Victor, or other, laterally cut record is to be played, a stylus 12 is fitted to the socket-piece 11; as shown in Figs. 1 and 2, and the disk 23 is adjusted by turning the knob 19 until the counterweight 24 is directly behind the sight opening 29, or is in its intermediate position directly above the axis of the swivel joint of the tone-arm extension. The disk is maintained in this position by friction of a spring 30, Fig. 2, confined in a recess 31 in the rear side of the disk 27 and bearing against the front face of the counterweighted disk. When an Edison or Pathé record, or other record of the vertically cut type is to be played, the stylus 12 is withdrawn, and a suitable stylus is mounted in the socket 14, and the counterweighted disk is then shifted to one side or the other until the shoulder 25 or the shoulder 26 comes into contact with the lug 18. Such shifting of the counterweighted disk brings into view, through the sight opening 29, the name indicating the make or character of the disk being played. If it is an Edison disk, the normal weight of the sound-box and tone-arm extension is lessened, because the counterweight is on the opposite side of the swivel axis from the sound-box. If it is a Pathé disk, the normal weight of the sound-box is increased, because the counterweight is then on the same side of the swivel axis as the sound-box. It will thus be seen that this feature of my invention provides a simple and effective means for varying the weight effect of the sound-box and stylus on the record so as to produce the most effective results.

It is believed that the principles, mode of manipulation, and mechanical advantages of the invention will be understood and appreciated by those skilled in the art from the foregoing description and illustration; and, hence, without limiting myself to the particular details of structure and arrangement shown and described,

I claim:

1. The combination with a swiveled tone arm extension, and a sound box connected to the free end of said extension, of a weight mounted on said tone arm extension with capacity for adjustment to either side of the swivel axis of the latter.
2. The combination with a swiveled tone arm extension, and a sound box connected to the free end of said extension, of a weight mounted on said tone arm extension with capacity for adjustment to either side of the swivel axis of the latter, and an indicator plate having a sight opening through which indicia on the face of said weight may be brought into view as the weight is shifted from one position to another.
3. The combination with a swiveled tone-

arm extension, and a sound-box connected to the free end of said extension, of a disk pivotally mounted on said extension concentric with the swivel axis of the latter, an eccentric weight carried by said disk, and stop means for limiting the turning movement of said disk in both directions.

4. The combination with a swiveled tone-arm extension, and a sound-box connected to the free end of said extension, of a disk pivotally mounted on said extension concentric with the swivel axis of the latter, an eccentric weight carried by said disk, manually operable means for turning said disk so as to shift said weight from one side to the other of said swivel axis or to an intermediate position, and stop means for limiting the turning movement of said disk in both directions.
- 10 5. The combination with a swiveled tone-arm extension, and a sound-box connected to the free end of said extension, of a disk pivotally mounted on said extension concentric with the swivel axis of the latter and bearing record indicia on one face thereof, an eccentric weight carried by said disk, manually operable means
- 15
- 20
- 25

for turning said disk so as to shift said weight from one side to the other of said swivel axis or to an intermediate position, 30 a stationary plate having a sight opening for said indicia located in front of said disk, and stop means for limiting the turning movement of said disk in both directions. 35

6. The combination with a swiveled tone-arm extension, and a sound-box connected to the free end of said extension, of a disk pivotally mounted on said extension concentric with the swivel axis of the latter 40 and bearing record indicia on one face thereof, an eccentric weight on the opposite face of said disk, manually operable means for turning said disk so as to shift said weight from one side to the other of 45 said swivel axis or to an intermediate position, a stationary plate having a sight opening for said indicia located in front of said disk, stop means for limiting the turning movement of said disk in both directions, 50 and means for holding said disk against turning when in an intermediate position.

ALBERT A. HUSEBY.
